US0D1013034S

(12) **United States Design Patent** (10) **Patent No.:** **US D1,013,034 S**
(45) **Date of Patent:** ** **Jan. 30, 2024**

(54) **ENGRAVING MACHINE**

(71) Applicant: **Foshan Nanhai Puruite Technology Co., Ltd**, Foshan (CN)

(72) Inventors: **Jun Yang**, Foshan (CN); **Wei Luo**, Foshan (CN)

(73) Assignee: **Foshan Nanhai Puruite Technology Co., Ltd**

(**) Term: **15 Years**

(21) Appl. No.: **29/834,582**

(22) Filed: **Apr. 13, 2022**

(51) **LOC (14) Cl.** **15-09**

(52) **U.S. Cl.**

USPC **D15/122**; D18/57

CPC **B23C 9/00** (2013.01)

(57) **CLAIM**

We claim the ornamental design for a engraving machine, as shown and described.

DESCRIPTION

FIG. 1 is a front perspective view of a engraving machine showing my new design;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The broken lines in the drawings depict portions of the engraving machine that form no part of the claimed design.
